WILLIS ENGLES, OF PAW PAW, MICHIGAN.

INTERNAL-COMBUSTION TURBINE-ENGINE.

1,105,500.

Specification of Letters Patent. Patented July 28, 1914.

Application filed May 27, 1913. Serial No. 770,187.

To all whom it may concern:

Be it known that I, WILLIS ENGLES, a citizen of the United States, residing at Paw Paw, in the county of Van Buren and State of Michigan, have invented new and useful Improvements in Internal-Combustion Turbine-Engines, of which the following is a specification.

This invention relates to internal combustion turbine engines the object of the invention being to produce a simple reliable engine of the class described which is economical in construction and in consumption of fuel and in which the gas or mixture of gas and air is efficiently compressed before being ignited and exploded, the compressed gas, upon the explosion and during the expansion thereof being delivered to the vanes of the rotor and imparting rotary motion to the latter is will hereinafter appear.

With the above and other objects in view the invention consists in the novel construction, combination and arrangement of parts hereinafter fully described, illustrated and claimed.

In the accompanying drawings: Figure 1 is a longitudinal section taken centrally through a motor embodying the present invention, the suction and compression piston being shown about midway of its stroke. Fig. 2 is a similar view showing the approximate position of the parts at the time of ignition. Fig. 3 is an enlarged longitudinal section through one end of the engine showing the worm, traveler and guides. Fig. 4 is a cross section on the line 4—4 of Fig. 1. Fig. 5 is a detail perspective view of the traveler.

The casing of the engine contemplated in this invention comprises a cylinder 1 and a rotor chamber 2, the same being in communication with each other by means of the reduced neck 3 at the inner end of the rotor casing 2. The rotor casing 2 is substantially frusto-conical in longitudinal section and round in cross section and is provided at its outer larger end with a reduced bearing sleeve 4 in which the outer end portion 5 of the rotor shaft is journaled. The main body 6 of the rotor shaft extends axially through the cylinder 1 as shown and adjacent to the junction of the cylinder 1 and the rotor casing 2, said shaft is reduced as shown at 7 to form an annular gas port 8 through which the expanding gas may pass from the cylinder 1 into the casing 2, when

the compression abutment is shifted toward the rotor end of the cylinder 1 where said cylinder is closed by the head 8. The rotor 9 corresponds in shape to the casing 2, being generally conical while the outer larger end thereof is rounded or of spherical section as indicated at 10; the outer end wall 11 of the casing 2 is correspondingly shaped. The dimensions of the rotor 9 and the casing 2 are so relatively proportioned as to leave an annular space 12 within the casing 2 and around the rotor 9 and also an end space 13 between the larger end 10 of the rotor and the end wall 11 of the rotor casing, said end wall 11 being provided with exhaust ports 14 through which the expanding gas may escape to the atmosphere. The rotor 9 is provided on the outer side thereof with spirally disposed vanes 15 against which the expanding gas impinges and presses in its movement from the cylinder 1 to the exhaust ports at the opposite end of the rotor casing, thereby imparting rotary motion to the rotor and the shaft 6.

Working within the cylinder 1 is a disk shaped abutment 16 which is arranged near the head 8 of the cylinder and yieldingly held away from the same by means of compression springs 17 interposed between said abutment and cylinder head as shown. The abutment 16 surrounds the shaft 6 and has a central opening 18 therein closely approximating in size or outside diameter to the shaft 6. The abutment 16 normally occupies the position shown in Fig. 1 in which it cuts off communication between the compression and expansion chamber 19 of the cylinder 1 and the rotor casing. A slight movement, however, of the abutment 16 toward the head 8 will open up the gas port 7 above referred to and permit the expanding gas to pass into the rotor casing 2.

20 designates a gas inlet port through which the mixture is admitted under pressure from a mixing valve or carburetor.

21 designates a suction and compression piston which is mounted to reciprocate in the cylinder 1, said piston surrounding and sliding on the shaft 6 which rotates therein. The piston 21 is non-rotating and has rigidly attached thereto a tubular piston rod 22 which closely surrounds the shaft 6 and extends rearwardly with a snug sliding fit through a central opening 23 in the head 24 of the cylinder opposite the head 8.

The cylinder 1 is formed beyond the head

24 with a reduced cylindrical extension 25 for a purpose which will appear, the shaft 6 being reduced at 26 to form a stem or spindle 27 on which is mounted fast a worm 28 which rotates with the spindle 27 and the shaft 6. Upon the inside of the extension 25 and at opposite sides of the spindle 27 are parallel guide ways each embodying two parallel grooves 29 and 30 which connect at their opposite ends, the guide ways extending throughout the length of the worm 28.

A traveler 31 threaded upon its inner face as shown at 32 is carried by the tubular piston rod 22 and is mounted for movement 15 toward and away from the worm 28 so that it may be thrown into and out of engagement with said worm. This is accomplished by providing the traveler 32 with oppositely projecting pins or trunnions. These pins in 20 traveling in the grooves 30 serve to hold the traveler in engagement with the worm 28 but in the return movement of the traveler, the pins 33 move along the grooves 29 and thereby hold said traveler out of engagement 25 with said worm. In the movement of the traveler toward the cylinder 1, the pins 33 strike against spring switches 34 which act on said pins to throw the traveler away from and out of engagement with the worm so 30 that in the return movement of the traveler the pins 33 traverse the grooves 29 until the opposite ends of the grooves 29 are reached whereupon the pins 33 are free to be deflected inwardly again into the grooves 30.

35 designates a governor of the ball and arm type, said governor embodying a sliding collar 36 which as the governor slows down, comes in contact with an arm 37 on the traveler 32 and presses said traveler into 40 threaded engagement with the worm whereupon the rapidly revolving worm feeds the traveler 32 toward the cylinder 1 and as said traveler is attached to the tubular piston rod 22 the piston 21 is forced toward 45 the abutment 16, thereby compressing the gas which has previously been trapped in the combustion chamber. Just before the traveler reaches the inner limit of its movement the compressed charge is ignited and 50 expanded, displacing the abutment 16 and passing into the rotor chamber where it acts on the rotor. During the explosion, the piston is held against return movement by the traveler. As soon as the traveler 32 reaches the inner limit of its movement after 55 an explosion takes place and is tripped, the piston 21 is quickly drawn back by the rarefaction of the air in the suction chamber 38 formed by the rear end of the cylinder 1. 60 During such return movement of the piston 21 a partial vacuum is produced in the combustion chamber and a fresh charge of gas is sucked in through the inlet 20 which is controlled by a check valve. After an explosion the piston 21 lies close to the abut-

ment 16 the expanded gas having been expelled from between said parts. In other words, when the piston 21 is at the end of that stroke in which it approaches the abutment 16, the latter is forced toward the piston 21 by means of the spring 17 which closes the port 7 before the piston 21 starts to move away from the abutment. Therefore, when the piston 21 is carried away from the abutment 16, a fresh charge of explosive mixture is drawn into the explosion chamber 19 through the inlet 20 preparatory to compressing and firing the same as hereinabove described.

Any suitable ignition apparatus may be 80 employed to ignite the gas in the combustion chamber and the ignition apparatus may be driven from the rotor shaft and properly timed to furnish the spark just after the gas has been fully compressed between the members 21 and 16, the compression abutment 16 being supported by the springs 17, the latter being of sufficient tension to sustain the abutment 16 against compression during the compression stroke of the piston 21. As 90 soon as the explosion occurs the abutment 16 is displaced by the force of the explosion and the expanding gas rushes through the rotor casing acting on the vanes of the rotor in the manner and for the purpose described. 95

If desired air inlet valves 39 may be provided at the points shown to admit fresh air to the space between the abutment 16 and the cylinder head 8 as the abutment moves away from said cylinder head, said valves 100 being of the usual check type. Furthermore, a check valve 40 may be placed in the head 24 of the cylinder to insure the retention of the necessary partial vacuum in the suction chamber 38. 105

What is claimed is:

1. An internal combustion turbine engine, comprising a cylinder, a reciprocatory piston working therein, a rotor provided with vanes, a rotor casing located at one end of 110 said cylinder and in communication with the combustion space thereof, a rotor shaft carrying said rotor and extending through said piston, a displaceable compression abutment, automatically controlling said communication, and means actuated by said shaft for advancing said piston in its compression stroke.

2. An internal combustion turbine engine, comprising a cylinder, a reciprocatory piston working therein, a rotor provided with vanes, a cone shaped rotor casing located at one end of said cylinder and in communication with the combustion space thereof, a rotor shaft carrying said rotor and extending through said piston, a displaceable compression abutment, automatically controlling said communication, and means actuated by said shaft for advancing said piston in its compression stroke. 120 125 130

3. An internal combustion turbine engine, comprising a cylinder, a reciprocatory piston working therein, a rotor provided with vanes, a rotor casing located at one end of said cylinder and in communication with the combustion space thereof, a rotor shaft carrying said rotor and extending through said piston, said shaft being provided with a circular gas port, a displaceable compression abutment, automatically controlling said communication, and means actuated by said shaft for advancing said piston in its compression stroke.

4. An internal combustion turbine engine, comprising a cylinder, a reciprocatory piston working therein, a rotor provided with vanes, a rotor casing located at one end of said cylinder and in communication with the combustion space thereof, a rotor shaft carrying said rotor and extending through said piston, a displaceable compression abutment, surrounding said shaft and working at its periphery in contact with the cylinder wall automatically controlling said communication, and means actuated by said shaft for advancing said piston in its compression stroke.

5. An internal combustion turbine engine, comprising a cylinder, a reciprocatory piston working therein, a rotor provided with vanes, a rotor casing located at one end of said cylinder and in communication with the combustion space thereof, a rotor shaft carrying said rotor and extending through said piston, a displaceable compression abutment automatically controlling said communication, a tubular piston rod extending from said piston through the cylinder head and embracing said shaft, and means for throwing said rod and shaft into and out of engagement at opposite ends of the throw of the piston whereby said piston is advanced in its compression stroke by said shaft and released at the limit of said stroke.

6. An internal combustion turbine engine, comprising a cylinder, a reciprocatory piston working therein, a rotor provided with vanes, a rotor casing located at one end of said cylinder and in communication with the combustion space thereof, a rotor shaft carrying said rotor and extending through said piston, a displaceable compression abutment automatically controlling said communication, a tubular piston rod extending from said piston through the cylinder head and embracing said shaft, and means for throwing said rod and shaft into and out of engagement at opposite ends of the throw of the piston whereby said piston is advanced in its compression stroke by said shaft and released at the limit of said stroke, the cylinder being closed in rear of said piston to form a vacuum chamber for effecting the return movement or suction stroke of said piston.

7. An internal combustion turbine engine, comprising a cylinder, a reciprocatory piston working therein, a rotor provided with vanes, a rotor casing located at one end of said cylinder and in communication with the combustion space thereof, a rotor shaft carrying said rotor and extending through said piston, a displaceable compression abutment automatically controlling said communication, a tubular piston rod extending from said piston through the cylinder head and embracing said shaft, means for throwing said rod and shaft into and out of engagement at opposite ends of the throw of the piston whereby said piston is advanced in its compression stroke by said shaft and released at the limit of said stroke, and a suction chamber for effecting the return movement or suction stroke of said piston.

8. An internal combustion turbine engine, comprising a cylinder, a reciprocatory piston working therein, a rotor provided with vanes, a rotor casing located at one end of the cylinder and in communication with the combustion space thereof, a rotor shaft carrying said rotor and extending through said piston, a displaceable compression abutment automatically controlling said communication, a tubular piston rod extending from said piston through the cylinder head and embracing said shaft, means for throwing said rod and shaft into and out of engagement at opposite ends of the throw of the piston whereby said piston is advanced in its compression stroke by said shaft and released at the limit of said stroke, said means including a worm on the rotor shaft, and a threaded traveler carried by said piston rod.

9. An internal combustion turbine engine, comprising a cylinder, a reciprocatory piston working therein, a rotor provided with vanes, a rotor casing located at one end of the cylinder and in communication with the combustion space thereof, a rotor shaft carrying said rotor and extending through said piston, a displaceable compression abutment automatically controlling said communication, a tubular piston rod extending from said piston through the cylinder head and embracing said shaft, means for throwing said rod and shaft into and out of engagement at opposite ends of the throw of the piston whereby said piston is advanced in its compression stroke by said shaft and released at the limit of said stroke, said means including a worm on the motor shaft, a threaded traveler carried by said piston rod, and means for shifting said traveler into engagement with said worm at one end of the piston stroke and out of engagement therewith at the other end of the piston stroke.

10. An internal combustion turbine engine, comprising a cylinder, a reciprocatory

piston working therein, a rotor provided
 with vanes, a rotor casing located at one
 end of the cylinder and in communication
 with the combustion space thereof, a rotor
 5 shaft carrying said rotor and extending
 through said piston, a displaceable compres-
 sion abutment automatically controlling
 said communication, a tubular piston rod
 extending from said piston through the cyl-
 10 inder head and embracing said shaft, means
 for throwing said rod and shaft into and
 out of engagement at opposite ends of the
 throw of the piston whereby said piston is
 advanced in its compression stroke by said
 15 shaft and released at the limit of said stroke,
 said means including a worm on the rotor
 shaft, a threaded traveler carried by said
 piston rod, and guides along which said
 traveler moves acting to hold the traveler
 20 against the worm while moving in the oppo-
 site direction.

11. An internal combustion turbine en-
 gine, comprising a cylinder, a reciprocatory
 piston working therein, a rotor provided
 25 with vanes, a rotor casing located at one
 end of the cylinder and in communication
 with the combustion space thereof, a rotor

shaft carrying said rotor and extending
 through said piston, a displaceable compres-
 sion abutment automatically controlling 30
 said communication, a tubular piston rod
 extending from said piston through the cyl-
 inder head and embracing said shaft, means
 for throwing said rod and shaft into and
 out of engagement at opposite ends of the 35
 throw of the piston whereby said piston is
 advanced in its compression stroke by said
 shaft and released at the limit of said stroke,
 said means including a worm on the rotor
 40 shaft, a threaded traveler carried by said
 piston rod, guides along which said traveler
 moves acting to hold the traveler against the
 worm while moving in one direction and off
 the worm while moving in the opposite di-
 45 rection, and a governor acting to shift the
 traveler against said worm as the speed of
 the rotor shaft decreases.

In testimony whereof I affix my signature
 in presence of two witnesses.
